J. H. Bryant

UNITED STATES PATENT OFFICE.

MIKE LUTENBERGER, OF BLOCTON, ALABAMA.

CARBIDE CAN.

Application filed October 15, 1923. Serial No. 668,773.

To all whom it may concern:

Be it known that I, MIKE LUTENBERGER, a citizen of the United States of America, residing at Blocton, in the county of Bibb 5 and State of Alabama, have invented certain new and useful Improvements in Carbide Cans, of which the following is a specification.

This invention relates to certain new and 10 useful improvements in carbide cans and especially to a can of the portable type adapted to be carried by a miner during a working day and containing sufficient carbide and lamp accessories for use in case 15 of emergency.

The primary object of the invention is to provide a carbide can having a filling opening for carbides at one end thereof, the other end of the can carrying a receptacle 20 extending into the can body and having a closure opening outwardly of the carrying end of the can for the reception of lamp accessories such as a new spark, felt and rubber gasket or washers, a burner tip and a 25 wire cleaner, the lower end of the can carrying the receptacle further having a tube supported thereon and extending into the body of the can for housing a lamp pick or tip cleaner.

It is a further object of the invention to provide a protecting frame for the can that includes a band enclosing the lower end thereof and projecting outwardly of the can bottom to protect the can and tube supported and with the protecting frame further carrying a belt receiving attachment to facilitate carrying of the can by a miner.

With the above and other objects in view as the nature of the invention is better understood, the same consists of the novel form, combination and arrangement of parts hereinafter more fully described shown in the accompanying drawing and claimed.

In the drawing, wherein like reference characters designate corresponding parts throughout the several views,

Figure 1 is a front elevational view, partly broken away and shown in section of a carbide can constructed in accordance with the present invention showing the can filled with carbide and the bottom wall thereof supporting the inset receptacle for lamp accessories and the tube for a lamp pick with the protecting band for the lower end of the can projecting outwardly thereof,

Figure 2 is a side elevational view of the

can, with the protecting band at the lower end thereof partly broken away and shown in section.

Figure 3 is a top plan view, and

Figure 4 is a fragmentary detail sectional view of the upper end of the protecting frame for the can showing the belt retaining attachment.

Referring more in detail to the accompanying drawing, there is illustrated a carbide can having a body portion 1 slightly curved in its side walls and tapering toward its upper and lower ends with a removable screw cap 2 mounted upon the open upper 70 end thereof while the lower end is closed by a bottom wall 3, the can 1 being of the conventional type for containing carbide to be carried by miners.

In the use of a miner's lamp, it is quite frequently necessary during a day's work while in a mine to replace or renew certain lamp accessories such as a spark, burner tip, felt or gasket and when these accessories are carried in a pocket the same become lost or are damaged and are unfit for use, and it is therefore one of the important features of this invention to provide a receptacle in connection with the carbide can for safely carrying these accessories for use in connection with the lamp. As shown in Fig. 1, the bottom wall 3 of the can carries a receptacle 4 set into the body of the can 1 having an outwardly open closure 5 that is hinged to the receptacle at 6. The lamp accessories 7 above enumerated, or other articles are carried within the receptacle 4 and are easily accessible by opening the closure 5 when the can 1 is in an inverted position. It is also intended to support a tubular member 8 by the bottom wall 3 of the can to extend into the body thereof as shown in Fig. 1 for supporting a lamp pick or cleaner wire 9 carried by the rod 10 having a threaded portion 11 and a knurled head 12, the threaded portion 11 screwing into the internally threaded bearing end 13 of the tubular member 8. It will be seen that the receptacle 4 and tubular member 8 occupy a minimum of space within the body 105 of the can 1 and still permit sufficient carbide to be carried by the can for a day's use, the receptacle and tubular member constituting a safe means for carrying the lamp accessories and preventing loss thereof.

A protecting frame encloses the can 1 and includes a band 14, preferably formed of

cushion material, surrounding the lower end of the can and projecting outwardly thereof as illustrated in Fig. 1 to protect the receptacle 4 and tubular member 8. To retain the band 14 in position upon the lower end of the can, there is provided a pair of side rods 15 passing through the opposite sides of the band 14 and carrying bent ends 16 that are upwardly directed for engaging the bottom wall 3 of the can. The upper ends of the side rods 15 are associated with a collar 17 that encloses the upper end of the can, a lift extension 18 being carried by each side of the collar and being apertured for the passage of an internally threaded cap screw 19 that receives the upper threaded end 15* of the adjacent rod 15, tightening of the screws 19 causing the collar 17 to frictionally engage the upper end of the can wall and forcing the bent ends 16 of the side rods into binding engagement with the bottom wall of the can. To facilitate carrying of the can, a belt receiving loop 20 is carried by the collar 17 to permit the can 1 to be suspended from the waist line of the miner.

From the above detail description of the device, it is believed that the construction

and operation thereof will at once be understood, it being noted that the lamp accessories are safely carried in the receptacle 4 and tube 8 and are readily accessible by inverting the can 1. The protecting frame for the can prevents damage thereto while the receptacle and tubular member occupy a minimum of space within the can body so that a sufficient amount of carbide may be carried for a day's use.

While there is herein shown and described the preferred embodiment of the present invention, it is nevertheless to be understood that minor changes may be made therein without departing from the spirit and scope of the invention as claimed.

What is claimed as new is:—
In a carbide can including a body having a removable upper end closure, a smaller receptacle set into the lower end of the can having a closure opening outwardly thereof, a relatively long tubular member extending into the lower end of the can, a lamp pick disposed in the tubular member, and a protector for the lower end of the can and the side walls thereof.

In testimony whereof I affix my signature.
MIKE LUTENBERGER.
